Term of patent 14 years

(Cl. D26—5)

FIG. 1

FIG. 2

FIG. 1 is a perspective view of the left-hand side and front of the invention showing our design of a cabinet for a computer.

FIG. 2 is a view showing the right-hand side and rear of the design.

The panelled side not completely shown in FIG. 2 is the same in appearance as that side shown in FIG. 1.

We claim:

The ornamental design for a cabinet for a computer, substantially as shown and described.
